UNITED STATES PATENT OFFICE.

WALTER E. EMERY, OF PEORIA, ILLINOIS.

TIME-CONTROLLED FURNACE-STARTER.

1,246,897.

Specification of Letters Patent. Patented Nov. 20, 1917.

Application filed February 9, 1917. Serial No. 147,638.

To all whom it may concern:

Be it known that I, WALTER E. EMERY, a citizen of the United States, residing at Peoria, in the county of Peoria, State of Illinois, have invented a new and useful Time-Controlled Furnace-Start; and I do hereby declare the following to be a full, clear, and exact description of the invention, such as will enable others skilled in the art 10 to which it appertains to make and use the same.

The present invention relates to a time controlled fire starting device, and has for its object to provide a device of this character which embodies novel features of construction whereby the dampers of a furnace which have been previously set to check the fire can be automatically released and shifted in their positions to start the fire and cause 20 it to burn.

Further objects of the invention are to provide a time controlled furnace starter which is comparatively simple and inexpensive in its construction, which can be readily attached to any conventional construction of stove or furnace, which is dependable in its operation, and which will enable a previously banked furnace fire to be automatically started at a predetermined time in the 30 morning so as to heat the house before the time for rising.

With these and other objects in view, the invention consists in certain novel combinations and arrangements of the parts as will 35 more fully appear as the description proceeds, the novel features thereof being pointed out in the appended claims.

For a full understanding of the invention, reference is to be had to the following description and accompanying drawings, in which:

Figure 1 is a side elevation of a conventional form of furnace having the fire starter applied thereto.

Fig. 2 is a detail perspective view of the trip means for controlling the fire starter.

Figs. 3 and 4 are detail views of a special form of trip mechanism constructed for actuation by an ordinary clockwork to release the trip finger at a predetermined time.

Corresponding and like parts are referred to in the following description and indicated in all the views of the drawings by the same reference characters.

For the purpose of illustration the fire starter is shown as applied to a conventional

furnace A, the numeral 1 designating the door for controlling the direct draft through the ash pit, and 2 the door for controlling the check or cold air draft in the smoke pipe. 60 3. The mechanism may be supported in any suitable manner, although in the present instance a platform or base 4 is shown as arranged upon the furnace A. A substantially 65 horizontally disposed cable 5 extends over the platform 4, the ends thereof being carried downwardly around suitable guide pulleys 6 and operatively connected to the direct draft 1 and check draft 2, respectively. 70 The guide pulleys 6 are shown as carried by bracket arms 7 projecting from the platform 4, and the cable 5 is of such a length that when the check draft 2 is closed the direct draft 1 is open, and vice versa. If necessary, 75 suitable means such as the weight 8 upon the cable 5 may be provided for normally moving the cable to close the check draft 2 and open the direct draft 1, this being the adjustment which is required for starting the fire. 80

An intermediate portion of the horizontally disposed cable 5 is engaged by a vertically disposed trip lever 9, said lever being longitudinally slotted at 10 to receive the cable and being pivotally mounted at its 85 upper end upon a standard 11 projecting from the platform 4. A knob or enlargement 12 in the cable 5 engages the slotted portion 10 of the lever to swing the lever to one side when the cable is released and permit it to move into such a position as to close the check draft 2 and open the direct draft 1. This position of the parts is indicated by Fig. 1.

The lower end of the trip lever 9 is arranged for engagement with a comparatively short horizontally disposed trip arm 13 which is rigid with a longer trip arm 14. In the present instance these two trip arms 13 and 14 are formed from a single length 100 of wire which is coiled at the junction of the trip arms to provide an eye 15 which is pivoted upon the standard 11, being confined against up and down movement thereon by the collars 16. The short arm 13 projects into the path of the lower end of the vertically swinging trip lever 9, while the long arm 14 is designed to be engaged by the trip finger 17 of a clockwork or time controlled mechanism 18 which is suitably 105 mounted upon the platform 4. Referring to Figs. 3 and 4, the numeral 19 designates the frame of the clockwork mechanism, and 20 a shaft which is provided at the rear end

thereof with a finger piece 21 and at the forward end thereof with a pointer 22 adapted to play over the numerals of a small dial in the same manner as the small pointer 5 of an ordinary alarm clock, and to be set at any desired position, according to the particular time when it may be desired to release the trip mechanism. A pinion 23 is slidably mounted upon the shaft 20 and 10 geared to the clockwork mechanism in the usual manner so as to make one complete revolution every twelve hours. A boss 24 on the pinion 20 is notched or recessed at 25 to receive a finger 26 on the shaft 20. This 15 finger normally rides upon the edge of the boss 24 and holds the pinion 23 against movement on the shaft 20, due to the pressure of the resilient arm 27 against the pinion, although when the pinion has been 20 revolved by the clockwork mechanism to bring the notch 25 under the finger 26, the pinion is moved longitudinally upon the shaft by the spring 27, the laterally bent end 27^a of the spring simultaneously clearing and being 25 coming disengaged from a lateral arm 28 on a rock shaft 29. A second arm 30 on the rock shaft is engaged by a spring 31, so that as soon as the rock shaft is released it is 30 rotated, thereby swinging the trip finger 17 which is rigid therewith and projects upwardly through the top of the clock works, and disengaging the said trip finger from the trip arm 14. The pull upon the cable 5, caused by the weight 8 will then move the 35 cable and reverse the previous position of the dampers, closing the check draft 2 and opening the direct draft 1.

When using the device it will be obvious that upon retiring or fixing the fire for the 40 night, the device will be set to check the fire, the trip lever 9 being engaged by the trip arm 13, and the trip arm 14 being engaged by the trip finger 17 of the clock work mechanism, so as to hold the cable 5 against 45 the action of the weight 8 with the check draft 2 open and the direct draft 1 closed. The shaft 20 of the clockworks will be rotated until the small pointer 22 is positioned upon the dial according to the time in the 50 morning when it is desired to start the fire. The dampers will thus be held in position to check the fire until the proper time for starting it, when the movement of the pinion 23 will operate as previously described to release the trip finger 17 and permit the trip arms 13 and 14, together with the vertical lever 9 to be swung into inoperative positions as the cable 5 is moved by the action of the weight 8 and the position of the dampers 55 shifted to start the fire. The house can thus be heated in the morning before the time for rising, and the end of the cable 5 is detachably connected to the direct draft door 60

1 by means of a hook 32 so that it can be disengaged therefrom during the day, thereby 65 enabling the furnace to be manipulated and adjusted in the usual manner at all times except when the mechanism is set for an automatic starting of the fire at a predetermined time. 70

Having thus described the invention, what I claim as new and desire to secure by Letters Patent, is:—

1. A device of the character described including a horizontally disposed and longitudinally movable cable having a stop thereon, means acting upon the cable for moving it in one direction, a vertically disposed swinging lever pivoted at its upper end and having a slotted portion which loosely receives the cable and is engaged by the stop thereon, a horizontally swinging trip arm mounted to engage the lower end of the vertically disposed swinging lever and to coöperate therewith to hold the cable against 80 movement, and a time controlled trip finger for releasing the trip arm at a predetermined time. 85

2. A device of the character described, including a horizontally disposed and longitudinally movable cable, means acting upon the cable for moving it in one direction, a standard arranged adjacent to the cable, a vertically disposed swinging lever pivotally mounted upon the standard at its upper end 90 and engaging the cable at its lower end, a short horizontal trip arm and a long trip arm connected at their junction by a coil which pivotally engages the standard, the short trip arm being adapted to engage the vertical lever for coöperation therewith to hold the cable against movement, and a time controlled trip finger for engaging and automatically releasing the long trip arm at 95 a predetermined time. 100

3. A device of the character described, including a horizontally disposed and longitudinally movable cable, means acting upon the cable for moving it in one direction, a vertically disposed swinging lever engaging 110 the cable, a horizontally disposed trip arm engaging the vertically disposed lever for coöperation therewith to hold the cable against movement, a second trip arm having a spaced and parallel relation to the first mentioned trip arm and rigid therewith, and a time controlled trip finger for engaging the second trip arm and releasing it at a predetermined time. 115

In testimony whereof I have signed my name to this specification in the presence of two subscribing witnesses.

WALTER E. EMERY.
